UNITED STATES PATENT OFFICE.

OTTO R. STARKE, OF NEW YORK, N. Y., ASSIGNOR TO THE FERDINAND STRAUSS CORPORATION, OF NEW YORK, N. Y., A CORPORATION OF NEW YORK.

TAIL-WAGGING TOY.

Application filed February 10, 1927. Serial No. 167,119.

This invention relates to mechanical toys and may be embodied in a variety of different tail bearing toy animals, such as a toy rabbit, cat, dog and the like, and one of the objects of the invention is to produce such a toy that will greatly amuse children, and of simple and inexpensive construction.

Another object of this invention is to produce such a toy that upon exerting a stroking pressure upon the back of the animal, a wagging of the tail will ensue.

A still further object of the invention is to extend the tail beyond the tail wagging member, so as to give to the tail an additional wagging or flipping motion when actuated, to simulate the natural tail wagging movement of such an animal.

Further objects and novel features of construction will become apparent as the specification proceeds.

In the drawings forming a part of this specification:

Figure 1 is a side view of a tail bearing animal partly in section exposing my invention as applied thereto.

Figure 2 is a top plan view of the motor mechanism and

Figure 3 is a fragmental top plan view of the tail wagging operating means.

Referring to the drawings in detail, 5 indicates the body of a toy animal, the said body being preferably made of fabric and stuffed with any material suitable for this purpose. Within the body 5 there is suitably mounted a motor 6 provided with the usual winding key shaft 7 to which is secured a power spring 8 and a drive gear 9 in mesh with a pinion 10 secured to a gear 11 upon a shaft 12 rotatably mounted in a motor frame or housing 13. The gear 11 is in mesh with a pinion 14 secured to a gear 15 on a shaft 16 provided with an offset or crank portion 17 and mounted for rotation in the housing 13. A governor mechanism 18, associated with the gear 15, controls the speed of the motor.

A tail member 20 preferably made of fabric is sewn or otherwise movably connected to the body 5 and is operated for wagging movement by a tail wagging member 21 pivotally mounted by means of a stud 22 on a bracket 23 secured to the housing 13. The tail wagging member is provided at one end thereof with a portion 24 having a slot 25 in which the crank arm 17

on the shaft 16 operates to move or swing the tail wagging member from side to side to contact with the tail 20 and cause same to wag. A brake member 25^a is pivotally mounted on a pin 26, journalled in the bracket 23 and is normally forced against the tail wagging member by a tension spring 27 on the pin 26 and anchored at one end to the bracket 23, and the said brake is provided with stop portions 28 and 29 normally in frictional engagement with the tail wagging member 21.

The operation of the toy is as follows: After the motor is wound up, the toy is placed upon a table or upon the ground and a stroking pressure is applied to the back of the toy in the region 30 thereof, which pressure causes the brake to release the tail wagging member and permit the motor to operate and cause the crank 17 to swing the tail wagging member to alternately contact with one or the other side of the tail and wag same and cause the end thereof to have an additional flapping movement as shown in Figure 1, and thus simulate the natural tail wagging movement of an animal.

From the above, it will be seen that I have provided a toy having means to simulate the natural tail wagging movements of animals and thus interest and amuse children.

Having described my invention what I claim and desire to secure by Letters Patent is:

1. In a toy of the nature described, a body a tail movably connected to the body, a motor in the body, a tail wagging member extending into the tail and pivotally mounted in the body, a brake pivotally mounted on the motor in frictional engagement with the tail wagging member, and means on the motor in engagement with the tail wagging member to actuate same and wag the tail when the brake is released from the tail wagging member.

2. In a toy of the nature described, a body, a tail movably connected to the body, a motor in the body, a tail wagging member extending into the tail and pivotally mounted in the body, a slotted portion on the tail wagging member, and a crank shaft on the motor extending into the said slotted portion to actuate the tail wagging member to wag the tail.

3. In a toy of the nature described, a

body, a tail movably connected to the body, a motor in the body, a tail wagging member extending into the tail and pivotally mounted in the body, a brake pivotally mounted on the motor and in operative engagement with the tail wagging member, a slotted portion on the tail wagging member and a

crank shaft on the motor extending into said slotted portion to wag the tail when the brake is released from engagement with the tail wagging member. 10

In testimony whereof I hereunto affix my signature.

OTTO R. STARKE.
